JOHN J. HAMPSON, OF LONDON, ENGLAND.

MACHINE FOR FILLING OR LOADING FABRICS.

1,313,686.

Specification of Letters Patent.

Patented Aug. 19, 1919.

Application filed April 24, 1919. Serial No. 292,487.

To all whom it may concern:

Be it known that I, JOHN JAMES HAMPSON, a subject of the King of Great Britain, residing in London, England, have invented certain new and useful Improvements in Machines for Filling or Loading Fabrics, of which the following is a specification.

This invention relates to machines for impregnating or loading fabrics such as 10 cottons, twills and other materials with a filling of starchy or other liquid, the machines being of the kind that comprise a vat or tank to contain a supply of the filling liquid, devices for tensioning the fabric as 15 it is fed to a set of relatively adjustable rotary rolls, by which filling is conveyed from the tank and applied to the material, and one or more adjustably mounted doctors for removing surplus liquid from the 20 fabric and pressing the filling into the latter.

The present invention has for its object to provide an improved machine of the above kind which is so constructed and can 25 be so adjusted that the various impregnating and loading operations of back filling, back filling and skimming in one process, light skimming, heavy slop filling or heavy starching, double stiffening, and single stiffening can be alternatively effected by it, 30 each of which operations has at present to be carried out on a separate machine.

In a machine constructed according to this invention, there is a top or squeezing 35 roll vertically adjustable in position and two bottom rolls adapted to convey filling from the tank and apply it to the fabric to be treated. The two bottom rolls which are independently adjustable in horizontal di- 40 rections, are arranged tandem-wise, one on each side of, but at a lower level than the top roll. A doctor knife is so mounted on the frame of the machine that either it can be placed in a position between the two bot- 45 tom rolls so as to press against the fabric passing between these rolls, either in or out of contact with the surface of the top roll, or the doctor knife can be withdrawn from between the bottom rolls to a position out- 50 side of the working zone where it will take no part in a loading operation. Means are provided whereby, when the top roll is in use and the doctor knife is arranged and adjusted to press the fabric against that 55 roll, as in back filling and skimming, the

knife will bear on the fabric with a yielding pressure that may be varied, and when the top roll is not in use, but the knife has to press against the fabric, as for example in light skimming, the knife will be held in 60 proper operative position by the said means.

Means are included for turning the two bottom rolls according to circumstances in either direction of rotation. The mechanism for driving the bottom rolls is so constructed that the gears fixed to the roll spindles for turning the rolls will always remain in mesh with the gears that drive them, no matter how far the rolls may have been adjustably moved apart or shifted relatively to the top roll.

In using the improved machine, considerable economy in time, labor and working expenses results.

The invention will be described with reference to the accompanying drawings in which Figure 1, comprising Figs. 1^a and 1^b, is an elevation of one side of the improved machine in one of its forms.

Fig. 2, comprising Figs. 2^a and 2^b is a 80 longitudinal section of part of the machine viewed in the same direction as Fig. 1, the machine being shown and adjusted for the combined operations of back filling and skimming. Figs. 3 to 7 are diagrammatic 85 sections similar to Fig. 2, but to a smaller scale, showing the machine adjusted respectively for:—

- (a) Back filling.
- (b) Light skimming.
- (c) Heavy slop filling.
- (d) Double stiffening.
- (e) Single stiffening.

In the several figures the same parts are indicated by the same letter.

The machine is provided with three rolls 1, 2, 3 (between or over two or more of which the fabric, according to the operation to be performed, passes) carried in a suitable framework 4 and arranged for example 100 as in Fig. 1 so that lines connecting their axes 1', 2', 3' form a triangle, the two lower rolls 2 and 3, whose axes are in the base of the triangle, being partly located in a tank 5 for the liquid or filling. The three 105 rolls are mounted in bearings 1², 2², 3² respectively, which bearings are capable of being moved to and fro so that one or two nipping points may be provided between the 110 curved surfaces on the rolls or whereby the

rolls may be entirely separated. Two or more doctor knives 6, 7 are provided, knife 6 being mounted so that it can be arranged to operate between the lower pair of rolls 2 and 3, and so as to combine its action with the upper roll 1, and doctor knife 7 at the exit side of the said pair of rolls. Each knife is adjustable in position for the purpose of varying the pressure exerted by it on the 10 fabric or allowing it to be moved clear of same, as hereinafter described.

The knife 6 is clamped by means of a plate 6' and studs 6'' to a carrying member 6''' fixed to a spindle 6'', the two ends of which 15 are mounted in bearing blocks 6'''' arranged on each side of the machine. Each of these bearing blocks is mounted to slide in bracket guides 6'''''' suitably attached to a part of the framework 4 and in a position inclined to 20 the horizontal. Correlated with each block 6'''' by means of a screw thread connection is a rod 6'''''' one end of which is rotatively mounted in the lower end 6'''''''' of the corresponding bracket guide 6''''''. The other or 25 upper end of each rod 6'''''' passes through a cap piece 6'''''''' secured to the upper end of the bracket guide. The upper end of each rod 6'''''' carries a handwheel 6'''''''' or other device wherewith it may be turned. By turning the 30 handwheels 6'''''' and the rods 6'''''' the blocks 6'''''' can be shifted in one or other directions along the guideways of the bracket guides 6'''''', and the doctor knife 6 made to approach or recede from the cylindrical surface of the 35 roll 1 thereby varying or dispensing with the pressure of the knife on the underside of the fabric 67 passing under the roll 1. By operating the hand-wheels 6'''''' sufficiently the doctor knife 6 can, before the fabric is passed through the machine, be retracted from between the rolls to an inoperative position above roll 2 and to the left in Fig. 1, of roll 1.

Means are provided for rocking the doctor knife 6 about the axis of the spindle 6'' so as to vary its inclination with respect to the fabric and its pressure thereon. Such means may comprise a link 8 (or there may be two such links, one on each side of the 50 machine) having one of its ends detachably connected with an arm 6'''' carried by the member 6''' or spindle 6''. This link end may be of a form to hook on to a pin 6'''''' carried by the arm 6'''''. It would be unhooked therefrom when the doctor knife 6 is to be withdrawn clear of rolls 1 and 2 and the working zone of the machine as described above. The other end of link 8 is pivotally connected to an arm 9' of a crank lever 9 carried by a stub shaft 10 journaled in bracket bearings 11 mounted on the framework 4. If two links 8 be employed there will be two levers 9 which are operated for turning shaft 10 and thereby adjusting the 65 inclination of the knife 6 with respect to

the fabric and the vertical plane containing the axis of roll 1. The ends 9' of levers 9 carry each a suitable weight 12 which tends to turn the lever so as to cause the doctor knife 6 to impart pressure against the fabric. The action of the weights 12 will tend to prevent the doctor knife being depressed or turned by the motion of the fabric in contact with it, while allowing it to yield or turn about its axis to a small extent when meeting with joints or other irregularities in the thickness of the fabric. 75

Suitable means may be provided for retaining the levers 9, when desired, in any adjusted position. Such means may consist, for instance, of a pin 13 that is passed through a hole 9'' provided in the levers, and through one or other of the holes 14' formed in one of the uprights 14 hereinafter referred to and supported by the framework 4. The 80 knife 7 is clamped like knife 6 to a carrying member 15 which is fixed to a spindle 16 journaled in bearing blocks 17 slidably mounted in a pair of suitably formed upright guiding frames 18 fixed to the framework 4, one on either side thereof. The height of the knife 7 with respect to the roll 3 can be varied by raising or lowering the blocks 17 by operating the screwed rods 19 that are in screw threaded relation with 85 the blocks 17 and have their lower ends mounted to turn in the lower end of the guide frames 18. The rods 19 traverse the cap pieces 18' and are furnished at their upper ends with hand wheels or other devices 19' wherewith they may be turned. Means, such as the arm 15', screw-threaded rod 20, pivotally attached thereto and passing through an opening in a part 22 carried by the framework 4, and a nut 21, may be 90 provided for adjusting the inclination of knife 7 with respect to the fabric, and thereby varying the amount of filling in the 95 fabric.

The rolls 1, 2, 3 are arranged to be adjustable in position. In the form of the machine shown in the drawings the bearings 12 of the upper roll 1 are vertically adjustable in upright guides 23 by means of rods 24 which at the lower ends are attached to 110 the bearing blocks 12 and have their upper portions screw-threaded and are correlated with nuts having the form of worm wheels 25 each of which meshes with a worm 26.

The worms 26 are carried by a transverse 115 spindle 27 rotatably mounted at each end in brackets 28 carried by bosses 29' formed on levers 29 which are each pivoted at one end in supports 30 on the guide frames 23. Through the bosses 29' of levers 29 pass the 120 screw threaded portions of the rods 24 and on their upper surface the worm wheel nuts 25 are seated. The other ends of the levers 29 are each pivotally connected to one end of a link 31 which by means of an adjustable 125 130

screw coupling 31² at its other end is joined to a link 31' which in turn is pivotally attached to a lever 32 in turn pivoted at one end 32' to the framework 4, and at the other 5 end carries an adjustable weight 32². It will be seen that by means of this arrangement the roll 1 is suspended, being carried by the pair of pivoted levers 29 which are controlled by the pairs of adjustable links 10 31, 31'. The weights 32² carried by the levers 32 can be adjusted to place any desired pressure on the roll 1. By virtue of this arrangement roll 1 will, when it meets with any undue pressure, rise and yield to the 15 pressure but will subsequently return, when such pressure ceases, to the normal or initial position under the action of the weights 32² and associated parts.

The spindle 27 is provided with some convenient device, such as a crank handle, wherewith it and the worms thereon may be turned so that by the coöperative action of the screw rods 24 and worm wheel nuts, the bearings 1² and roll 1 may be raised or 20 lowered. Or the spindle 27 and worms 26 may be manually operated, as shown, by means of a chain 34 passing around a sprocket wheel 35 fixed to the spindle 27 and a similar wheel 36 rotatably mounted on a 25 spindle 36' carried by a frame 90 hereinafter referred to and carried by the framework 4. Studs 33, screw-threaded into the lower portion of each guide frame 23, serve to regulate the descent of the bearings 1² in the 30 guideways. The mechanism for driving roller 1 from the main driving shaft 37, as described below, is arranged to permit of the adjustments or movements described above, a drive in either direction and also 35 the discontinuance of the drive at any time. The wheel 36 if desired may be fitted with a handle 36² for turning it.

The lower rolls 2 and 3 are adjustable to and from each other, which may be arranged 40 by mounting their bearings 2' and 3' to slide in horizontal guideways 38' in guides 38. The bearings are moved along the guideways by means of the screw rods 39 and worm wheel nuts 40. The worm wheel nuts 45 40 can be turned by means of the worms 41 keyed to spindle 42 which would be provided with suitable means, such as the crank handle 43, for operating it.

Any suitable mechanism, however, which 50 will permit of a sliding adjustment, preferably by hand, and a drive in either direction from the main drive and a disconnection from the main drive of either roll or bowl may be employed. 55 The roll 1 is driven from the main driving shaft 37, on which are mounted fast and loose driving pulleys 44 operated from any suitable source of power. Shaft 37 carries a toothed wheel 45 in gear with a toothed 60 wheel 46 which is adapted to operate a wheel

47 keyed to the shaft 1' of roll 1. The wheel 46 is carried by a stub shaft 46' adjustably mounted in a curved slot struck from a point on the axis of shaft 37 and formed in a bracket supported from the framework 4, 70 so that the necessary adjustment of the position of wheel 46 can be effected, when the roll 1 is raised or lowered, by moving shaft 46' along the slot.

The rolls 2 and 3 are also driven from the 75 main driving shaft 37 by means of mechanism which permits of the rolls being adjusted in the manner above described and a reverse drive of either of the two shafts 2', 3' when desired, while they are in any position. 80 Such mechanism, as shown in the drawings, may include a pair of bevel wheels 48 loose on shaft 37 and in mesh respectively, at diametrical opposite points, with a bevel wheel 49 on the lower end of a vertical shaft 50 85 mounted in bearings 51, carried by a bracket 52 which is fixed to the framework 4, and a clutch device 53 mounted to rotate with shaft 37 and to slide along a feather thereon. The clutch 53 is slid along shaft 37 by 90 means of two arms 53' which are yoked at one end to the member 53 and at their other end fixed to a spindle 54 which is supported in bearings carried on brackets 55 attached to framework 4. The spindle 54 and clutch 95 member 53 are controlled by the hand lever 56 fixed to the end of the spindle which is turned in one direction or the other so that the member 53 clutches one or other of the bevel wheels 48 according to the direction in 100 which shaft 50 is to be driven. The upper end of shaft 50 carries a bevel wheel 57 which meshes with a bevel wheel 58 fixed to a keyed or feathered shaft 59. To each of the shafts 2' and 3' is keyed a bevel wheel 60 105 and with each wheel 60 there meshes a bevel wheel 61 capable of sliding along a key or feather on shaft 59. Each of the wheels 61 has a hub 61' on which is formed a groove in which fits the bifurcated end of a yoke piece 110 64 which at its other end encircles the roll shaft 2' or 3' as the case may be. It will be seen that as either the roll shaft 2' or 3' and the corresponding bevel wheel 60 are moved in a guideway 38' the corresponding yoke 115 piece and engaged bevel wheel 61 will be likewise moved so that the bevel wheel 61 remains in mesh with the bevel wheel on the roll shaft thus moved.

The tank 5 is provided, as is customary, 120 with one or more power driven agitators for the liquid. Two such agitators 62, 63, are shown in Fig. 1. They may be of wood and of rectangular or other design. They are mounted on the transversely disposed spindles 62' and 63' appropriately journaled in the sides of the tank. These spindles are provided each at one end with a pulley or sprocket wheel 62², 63² over which a belt or chain runs. On the other end of the spindle 130

62' is keyed a pulley or sprocket wheel 65 which is driven by a belt or chain from a wheel 66 fast on the driving shaft 37.

The fabric 67 is arranged to enter the machine over a fixed tensioning rail 68 and one or more tensioning bars or rods 68' which latter are carried by the uprights 14 above referred to. The fabric then preferably passes either over further fixed tensioning bars or rods or, according to the treatment to be carried out, through a tensioning frame which may, as shown, consist of a pair of pivoted disks 69 carried by the two uprights 14 and connected together by tension rods 70, about which the fabric passes. Suitable means may be provided for turning the disks and the rods carried by them in one direction or the other so as to vary the tension on the fabric. The disks are provided on their peripheral edges with holes in which a tongue 71' on a pivoted pawl 71 can be placed to hold the tensioning device in an adjusted position. The machine may be provided with a second tensioning device which consists of the bars or rails 89 which are carried by a bracket 90 on each side of the framework 4.

72 is a draw roller attached to a spindle 73 journaled at each end in bearings mounted on brackets 74 supported from the guide frame 23. This roller is adapted to be rotated by means of a pulley wheel 75 mounted at one end of spindle 73 and a belt 76 which also passes around a pulley wheel 77 keyed to the main driving shaft. 78 and 79 are rollers adapted to draw the loaded fabric passing over guide roller 72 toward mechanism, not shown, for folding or plaiting the fabric. The roller spindles 78' and 40 79' are carried in suitable bearings 80 and 81 bolted to an appropriately supported member 82 associated with the said plaiting mechanism. Roller 78 is adapted to be driven from the spindle of roller 79 by means of the pulley wheels 75' and 78' and belt 83, while roller 79 can be driven from the spindle of roller 78 by means of pulley wheels 78' and belt 84.

85 is a guide roller which is carried by two blocks 86 one on each side of the machine, each block being adjustably mounted to slide in a guideway 87' on a bracket 87, supported on the framework 4 when the screwthreaded rod 88 is operated.

55 If the operation to be carried out is that of back filling, the rolls are adjusted so as to be separated apart as in Fig. 3 and the fabric 67 after passing through the tension devices may pass over the first of the lower rolls, 60 above the first doctor knife which presses it against the under side of the upper roll 1 to remove the surplus starch or other liquid and then passes out over the draw roller 72 for plaiting or other purposes. In this case the lower roll may be driven in the reverse

direction to the upper as indicated by the arrows on the rolls in Fig. 3. For back filling and skimming as illustrated in Fig. 2, all three rolls 1, 2 and 3 may be driven in the same direction and the fabric may 70 pass over both lower rolls and both doctor knives 6 and 7, the first of which exerts pressure on the fabric from the under side against the upper roll, while the second on the exit side of the last lower roll may exert 75 pressure on the under side of the fabric without any support for the fabric above. The fabric in this case may conveniently pass out over the adjustable guide roller 85.

For light skimming, Fig. 4, the upper roll 80 is not employed, the two lower rolls being driven in the direction of travel of the fabric, which is in contact with the upper portions of the rolls, the first doctor knife 6 pressing against the under surface of the 85 fabric, but not pressing the latter against the upper roll which for this purpose has been moved away from the fabric.

For heavy slop filling or heavy starching, Fig. 5, the three rolls are moved into nipping 90 contact as shown; the lower rolls are driven in the direction of the fabric's travel while the upper roll 1 may or may not be driven and the fabric passes around the second lower roll 3 and under and partly around the upper roll, the doctor knives 6 and 7 being preferably moved out of action. For double stiffening, Fig. 6, the arrangement of the three rolls is the same, but the fabric travels under the upper roller only 100 and over the two lower rolls. In this case the tension device comprising the bars or rails 89 is brought into use, in lieu of or in addition to the tensioning device 69, 70.

For single stiffening, Fig. 7, the upper and 105 first lower rolls only are in contact, the upper being free to revolve and the lower being driven in the direction of the fabric's travel, the second lower roll being moved out of contact with the fabric which passes, as 110 for double stiffening, between a lower and the upper roll.

In none of the last mentioned three arrangements need the doctor knives be used, though one or more of the tension devices 115 would be.

Other variations of the position of the rolls, the drive of the same, and the amount of pressure (or absence) of the doctor knives are possible, according to the amount of 120 starch or other liquid it is desired to incorporate in the fabric, and a drive of a lower roll (or rolls) may be arranged in the reverse direction to the travel of the fabric incorporating more starch or the like into it. 125

Having thus described the nature of the said invention and the best means I know of carrying the same into practical effect, I claim:

1. In a filling loading or impregnating 130

- machine of the class specified, a plurality of rolls, one of which is above the others and all having means to permit them to be moved toward and from each other, a filling tank 5 in which a part of the rolls operate, and doctor knives adjustably disposed in a plane between and at a distance from the rolls to carry on either of the respective operations of back filling, back filling and skimming, 10 light skimming, heavy slop filling, double stiffening and single stiffening in a unitary machine.
2. In a filling loading or impregnating machine of the class specified, a vertically 15 adjustable top squeezing roll, a pair of horizontally adjustable bottom rolls arranged in tandem, a filling containing tank having the bottom rolls operating therein to convey the filling to the fabric to be treated, and a 20 movable doctor knife below the top roll and between the bottom rolls and having means for shifting the blade thereof into and away from an operative position relatively to the fabric and top roll.
- 25 3. In a filling loading or impregnating machine of the class specified, a vertically adjustable top squeezing roll, a pair of horizontally adjustable bottom rolls arranged in tandem, a filling containing tank having the 30 bottom rolls operating therein to convey the filling to the fabric to be treated, and a doctor knife below the top roll and between the bottom rolls and provided with adjusting means to cause the blade thereof to bear with 35 a yielding pressure against the fabric and the top roll when the latter is in use.
4. In a filling loading or impregnating machine of the class specified, a vertically 40 adjustable top squeezing roll movable out of engagement with the fabric treated, a pair of horizontally adjustable bottom rolls arranged in tandem, a filling containing tank having the bottom rolls operating therein to convey the filling to the fabric to be treated, 45 and a shiftable doctor knife below the top roll and between the bottom rolls and having means for retaining the blade thereof in an operative position relatively to the fabric when the top roll is not in use.
- 50 5. In a filling loading or impregnating machine of the class specified, a top squeezing roll, a pair of horizontally adjustable bottom rolls arranged horizontally in tandem, a filling containing tank having the bottom rolls operating therein to convey 55 the filling to the fabric, a doctor knife below the top roll and between the bottom rolls, shafts for said bottom rolls, a main driving shaft to which the shafts of the bottom rolls are geared, and means whereby each of the 60 bottom rolls and its shaft can be turned in either direction of rotation.
6. In a filling loading or impregnating machine of the class specified, a top squeezing roll, a pair of horizontally adjustable 65 bottom rolls arranged horizontally in tandem, a filling containing tank having the bottom rolls operating therein to convey the filling to the fabric, a doctor knife below the top rolls and between the bottom rolls, 70 shafts for said bottom rolls having gears mounted thereon, a main shaft having driving gearing in mesh with the bottom roll gears and means whereby the gears of the shafts of the bottom rolls may be moved uniformly with the said shafts and the latter rolls and be retained in mesh with the gearing of the main driving shaft.
7. In a filling loading or impregnating machine of the class specified, a vertically 75 adjustable top squeezing roll, a pair of horizontally adjustable bottom rolls having shafts provided with operating gears, a filling containing tank in which the bottom rolls operate to convey the filling to the 80 fabric, a doctor knife below the top roll and between the bottom rolls and provided with an adjustable blade and means for bodily moving it at an angle, a main shaft having driving gearing in mesh with the bottom roll 85 gears, a doctor knife at the exit side of the bottom rolls, and means whereby the gears of the shafts of the bottom rolls may be moved uniformly with the said latter shafts and rolls and be retained in mesh with the 90 gearing of the main shaft.
- In testimony whereof I have signed my name to this specification.

JOHN JAMES HAMPSON.
